US00D619905S

(12) **United States Design Patent**
Dunn et al.

(10) **Patent No.:** US D619,905 S
(45) **Date of Patent:** ** Jul. 20, 2010

(54) **DIAPER PAIL BAG**

(75) Inventors: **Steven B. Dunn**, Beverly Hills, CA (US); **Mark A. Hatherill**, Beverly Hills, CA (US); **Kevin D. Johnson**, Tarzana, CA (US)

4,869,049 A 9/1989 Richards et al.
4,880,852 A 11/1989 Hoshino et al.
4,906,495 A 3/1990 Martini et al.
4,946,720 A 8/1990 Oishi et al.
4,948,266 A 8/1990 Bencic

(73) Assignee: **Munchkin, Inc.**, North Hills, CA (US)

(Continued)

(**) Term: **14 Years**

FOREIGN PATENT DOCUMENTS

(21) Appl. No.: **29/346,378**

WO 99/39675 A1 8/1999

(22) Filed: **Oct. 30, 2009**

(Continued)

(51) **LOC (9) Cl.** 09-05

(52) **U.S. Cl.** D9/703

(58) **Field of Classification Search** D9/702-706, D9/720, 734, 414, 424, 430-432, 907; D3/255, D3/276, 246, 201, 232, 240, 245; 150/107, 224/409; 383/6, 10, 24, 26

(74) *Attorney, Agent, or Firm*—Knoble Yoshida & Dunleavy, LLC

(57) **CLAIM**

The ornamental design for a diaper pail bag, as shown and described.

DESCRIPTION

FIG. 1 is a perspective view showing our new design;

FIG. 2 is a bottom plan view;

FIG. 3 is a top plan view;

FIG. 4 is a first side elevational view;

FIG. 5 is a second side elevational view;

FIG. 6 is a front elevational view; and,

FIG. 7 is a rear elevational view.

The broken lines in the drawings depict probable environment only and form no part of the claimed design.

1 Claim, 7 Drawing Sheets
